3,264,799 HEAT SEALING MEANS FOR PACKAGING MACHINES

John S. Bartlo, Longmeadow, Mass., and Volker R. Grundmann, Windsor, Conn., assignors to Package Machinery Company, East Longmeadow, Mass., a corporation of Massachusetts

Filed Sept. 9, 1963, Ser. No. 307,586
10 Claims. (Cl. 53—379)

The present invention relates to improvements in packaging machines and more particularly to improved means for heat sealing folded wrapper portions.

The object of the invention is to provide simple and inexpensive means for registering a heat seal pattern on the end faces or other faces of articles against which wrapper portions are folded and lapped so that the pattern is spaced from the corner edges of the article, and further to provide for such registration on a wide range of article sizes with a minimum of adjacent and a minimum need of change parts.

The present invention has general utility for all heat sealable wrapper materials, but finds particular advantage in sealing oriented polypropylene and similar materials wherein contact by the heat sealing with the corner edges of the articles is particularly undesirable.

In accomplishing applicant's stated objects, heat sealing mechanism is provided at the discharge end of the folding channel of a wrapping machine and articles having wrapper extensions folded against the opposed end faces of the articles are advanced therewith by conveyor means which maintain the articles in spaced relation. The heat sealing mechanism comprises heat sealing rollers mounted on opposite sides of the path of advance of the articles. The rollers each have a working cylindrical surface of a height less than that of the end faces of the articles, with the lower and upper edges of the working surface being spaced respectively beneath and above the upper and lower corner edges of the end faces of the articles. Means are provided for rotating the rollers at a rate such that the peripheral rate of the cylindrical working surfaces is substantially the same as the rate of advance of the articles. Means are provided for moving the articles into engagement with the end faces of each article in such timed relation that the rollers contact the articles at a point adjacent to and spaced from the leading corner edges thereof and then move the rollers out of engagement with the articles in such timed relation that the last point of engagement with the end faces is adjacent to and spaced from the trailing corner edges of the articles, thereby producing a heat sealed pattern on the end faces of the article which is registered in relation thereto and spaced inwardly from the four corner edges thereof.

Similarly, where wrapper extensions are folded against each other on the bottom or other face of an article, a single roll could similarly be employed and the same means employed to so register a heat sealed pattern on such other face.

The above and other related objects and features of the invention will be apparent from a reading of the following description of the disclosure found in the accompanying drawings and the novelty thereof pointed out in the appended claims.

In the drawings:

FIG. 1 is a perspective view of a wrapped article illustrating a heat seal as formed in accordance with the present invention;

FIG. 2 is a view in transverse section showing the discharge end of a wrapping machine incorporating the heat sealing mechanism of the present invention;

FIG. 3 is a plan view, with portions broken away, of the heat sealing mechanism;

2

FIG. 4 is a section taken on line IV—IV in FIG. 3;

FIG. 5 is a side elevation, partly in section, of the heat sealing mechanism;

FIG. 6 is a section taken on line VI—VI in FIG. 3; and

FIG. 7 is a schematic diagram of electric air circuits employed herein.

Referring now to the drawings, articles *a* are discharged from the folding channel of a wrapping machine by overhead conveyor flights 10 (FIGS. 2 and 3). The flights 10 are driven by known means and advance the articles *a* in spaced relation along a platform 12. The articles are guided by side rails 14 and are held down by top guides 15. Wrapper portions are folded against the end faces of each article *a* in a manner illustrated in FIG. 1 by known means in the folding channel. It will be apparent to those skilled in the art that the folded wrapper portions could have other configurations.

The present invention deals with the heat sealing of these folded wrapper portions as the articles are discharged from the wrapping machine. Heat sealing rollers 16 mounted on opposite sides of the path of advance of the articles *a* are employed for this purpose. The mounting of each roller 16 is substantially identical and counterparts of the described right hand mounting are provided for the left hand mounting.

Each roller 16 comprises a heated cylinder 18 (FIG. 6), having a plurality of rings 20 telescoped thereover.

The cylinder 18 is secured to a flange 24 formed at the upper end of a hollow spindle 26, by screws 28. The lowermost ring 20 rests on the flange 24 and the stack of rings plus spacers 30 (which are also telescoped over the cylinder 18) are held in place by a retainer 32 which is secured to the upper end of the cylinder 18 by screws 34.

The spindle 26 is rotatably mounted by bearings 36 at the free end of an arm 38. A slip ring assembly 40 is secured to the lower end of the spindle 26 and provides for flow of electrical current to heating elements (not shown) mounted within the cylinder 18. A junction box 42 is secured to the arm 38 and an electrical cable *c* provides current through brushes 44 (FIG. 2) engaging the slip ring assembly 40 to energize the above-mentioned heating elements. If desired, connections can also be made in a known manner for the thermostatic control of the heating elements.

The arm 38 is pivotally mounted on a post 46 (FIG. 6) which projects upwardly from a bracket 48. The bracket 48 (FIGS. 2, 3 and 5) is slidably mounted on a cross bar 50 with gib 52 secured thereto and embracing the cross bar. The bracket 48 is also supported by a rotating shaft 54 (FIG. 3 in particular) which is journaled by bearings 55 mounted in legs 57 of bracket 48 which straddle a spiral gear 56 mounted on the shaft 54. The gear 56 is keyed to a sleeve 58 which is slidable on the shaft 54 and held in fixed relation to the bearings 55 by snap rings 60. The gear is centered relative to the sleeve 58 by collars 62. A slide key 64 is received by slots in the sleeve 58 and shaft 54 to transmit rotation from the shaft 54 to the gear 56 and at the same time to permit sliding movement of the bracket 48 relative to the shaft 54 to thereby enable adjustment of the sealing mechanism for different package widths.

The gear 56 meshes with a gear 66 which is secured to a vertical shaft 68 that is journaled by bearings 70 on the bracket 48. A sprocket 72 is secured to the upper end of the shaft 68 and has a chain 74 trained therearound. The chain 74 is also trained around a sprocket 76 which is formed integrally with the spindle 26. An idler sprocket 78 is rotatably mounted on a slide 80 which is adjustable relative to the arm 38 to properly tension the chain 74. Screw 82 is provided to tighten the slide 80.

in an adjusted position for proper tension of the chain 74.

Shaft 54 is continuously rotated by the same power source as issued for the wrapping machine. The relative rollers 16 are selected so that the peripheral rate of the rings 20 are substantially the same as the rate at which the articles *a* are advanced by the conveyor flights at 10.

Oppositely threaded screws 102 are received by threaded members 104 on each of the brackets 48. Means are provided for rotating the screws 102 simultaneously to move the heat sealing elements inwardly or outwardly, as desired, to adjust for varying package widths.

Each roller 16 is moved into and out of operative engagement with the end faces of the articles by an air cylinder 84 (FIGS. 2, 3 and 5) having one end pivotally mounted on an extension 85 of the bracket 48 by a shoulder screw 86. The air cylinder 84 has a piston rod 88 projecting therefrom which is pivotally connected at 90 to a bell crank 92. The bell crank is pivotally mounted at 94 to a lug 96 projecting from the bracket 48. A pair of links 98 are connected at one end to the bell crank 92 and at their opposite ends to a lug 100 projecting from the arm 38. FIG. 3 illustrates the roller 16 in its operative position with the piston rod 88 fully projected. When the piston rod 88 is retracted, the arm 38, and with it the roller 16, is swung outwardly to a position spaced from the path of advance from the article *a*.

A pair of detector switches 106, 108 are provided for actuating movement of the roller 16 into and out of engagement with the end faces of the articles. These switches are respectively secured to plates 110, 112 by screws 114. The plates 110, 112 are secured to a central mounting pad 116 by a screw 118 passing through slots in the plates 110, 112 to provide for longitudinal adjustment of the switches 106, 108. The mounting pad 116 is secured to a bracket 120 by screws 122. The bracket 120 has a junction box 124 mounted thereon to provide for electrical connections to the switches 106, 108. The bracket 120 is itself secured to the cross bar 50 by screws 126. The switches have actuator arms 128, 130 respectively which project above the discharge platform 12 and are depressed to actuate the switches 106, 108.

FIG. 7 in a highly diagrammatical form indicates the electrical connections of the switches 106, 108. It will there be seen that these switches are connected in series with each other and in series with a four-way solenoid valve S across a current source. The solenoid valve controls flow of compressed air to opposite ends of the air cylinder 84. When either of the switches 106 or 108 is open, the solenoid valve is deenergized to maintain the heated rollers 16 in positions spaced from the path of advance of the articles. When both of the switches 106, 108 are closed, the solenoid valve is energized and flow of air is reversed to project the piston rod 88 and thereby displace the rollers 16 into positions engaging opposite end faces of the articles *a*.

In operation, as the leading edge of an article first depresses the arms 128 and then 130, the solenoid valve S is energized, causing the rollers 16 to swing into engagement with the opposed end faces of the article *a*. The timing is such that the rings 20 which actually contact the article *a* engage the end faces thereof at a point adjacent to, but spaced inwardly from, the leading corner edges of the article. Likewise, when the trailing edge of the article passes over the switch arm 128, the switch 106 is opened and the solenoid valve is deenergized, causing the piston rod 88 to retract and thereby space the roller 16 from the path of advance of the articles. Here again the timing is such that the last contact of the rings 20 with the end faces of the article is at a point adjacent to but spaced from the trailing corner edges of the articles. It will further be noted that the arrangement

of the rings 20 in a heightwise sense is such that the highest and lowest points of contact thereof are at points respectively spaced from and adjacent the upper and lower corner edges of the article. In this fashion it is possible to register a heat sealed pattern on the end faces of the article which is spaced from the four corner edges thereof.

This feature is of particular value in overcoming the tendency of wrapper films tending to thin out or burn through at the corner edges when heat sealing the folded wrapper ends. This is particularly true with less rigid article where conventional sealing means engaging the entire face of the article tend to concentrate heat and pressure on the wrapper film at the corner edges as the central portions of the end faces of the article are deflected.

The present invention finds even greater utility in sealing certain newly available wrapper films such as oriented polypropylene, where engagement of the heated element of the corner edge is particularly undesirable since there would be a tendency to substantially weaken the wrapper even if no thinning occurred. In this latter connection, it will be noted that the rings 20 have a finely divided knurled surface. This surface has been found particularly advantageous in overcoming the difficulties of heat sealing oriented polypropylene. The use of knurled surfaces as such is known in the art.

The present sealing mechanism further finds great utility in its ability to handle a wide range of sizes with a minimum of changeover time from one size to another. Thus, it has already been pointed out that the sealing mechanism is mounted for lateral movement to accommodate different width of articles. As for article length, little or no adjustment of the longitudinal position of the switches 106, 108 is required. Further, to this, the rings 20 are adapted to facilitate accurate registration of a heat sealed pattern for articles of different heights. The sealing rings 20 are for this reason of different heights and telescoped over the cylinder 18 simply by selecting the proper combination of rings 20 and placing the spacer 30 below the unneeded rings, any height of article within a given size range can be readily accommodated.

It will further be pointed out that actuation of the solenoid valve controlling flow of air to the cylinder 84 could also be provided for by the use of cam means rotating in fixed relation to the advance of the conveyor flights 10. Different lengths of articles would be accommodated by providing a variable cam construction known to those in the art which would give a variable energization time for the solenoid valve, dependent upon the length of article.

Again it will be pointed out that the same concepts could be employed where other configurations of wrapper folds are used, as for example, where the wrapper folds require the use of a single roll sealing against the bottom of the article.

Having thus described the invention, what is claimed as novel and desired to be secured by Letters Patent of the United States is:

1. In combination with a packaging machine having a folding channel for folding wrapper extensions in lapped relation against one face of articles advanced therethrough, means for advancing articles through the folding channel, heat sealing mechanism comprising a cylindrical heat sealing roller mounted in opposed relation to said one face, means for rotating said roller about an axis parallel to said one face and normal to the path of advance of the articles at a peripheral rate approximating the rate of advance of the articles, the axial length of the working cylindrical surface of the roller being less than that of the opposed one face of the articles and spaced inwardly from the ends thereof, and means for moving the roller into engagement with said one face of each article in such timed relation that the roller contacts said one face at a point adjacent to and spaced inwardly from the leading corner edge thereof and means for moving

the roller out of engagement with said articles in such timed relation that the last point of engagement with said one face is adjacent to and spaced from the trailing corner edge of the articles to thereby produce a heat sealed pattern on said one face of each article which is registered in relation thereto and spaced inwardly from the four corner edges thereof.

2. A combination as in claim 1 wherein the heat sealing roller comprises a central cylinder, a plurality of rings of different axial lengths telescoped thereover, and a spacer of lesser diameter than said rings telescoped over said cylinder and adapted to separate one or more of the rings having the specified axial length less than that of the one face of the article from the remainder of the rings and means for replaceably holding said rings and spacer in assembled relation on said cylinder whereby the rings and spacer may be readily positioned on said cylinder to obtain the proper axial length of working surface for engaging a wide range of article dimensions.

3. In combination with a packaging machine having a folding channel for folding wrapper extensions against the opposed end faces of articles, and means for advancing the articles from the folding channel in spaced relation, heat sealing mechanism comprising heat sealing rollers mounted on opposite sides of the path of advance of articles from the folding channel, said rollers each having a working cylindrical surface of a height less than that of the end faces of the articles and with the lower and upper edges spaced respectively beneath and above the upper and lower corner edges of the end faces of the articles, means for rotating the rollers at a rate such that the peripheral rate of said cylindrical surfaces is substantially the same as the rate of advance of the articles, and means for moving the rollers into engagement with the end faces of each article in such timed relation that the rollers contact the articles at a point adjacent to and spaced inwardly from the leading corner edges thereof, and means for moving the rollers out of engagement with the articles in such timed relation that the last point of engagement with said end faces is adjacent to and spaced from the trailing corner edges of the articles to thereby produce a heat sealed pattern on the end faces of each article which is registered in relation thereto and spaced inwardly from the four corner edges thereof.

4. A combination as in claim 3 wherein each roller comprises a central cylinder, a plurality of rings of different heights telescoped thereover and a spacer of lesser diameter than said rings also telescoped over said cylinder and adapted to separate one or more of the lower rings having the specified height less than that of the article end faces from the remainder of the rings and means for releasably holding said rings and separator in assembled relation on said cylinder whereby the rings and separator may be readily positioned on said cylinder to obtain the

proper height of surface for engaging a wide range of article heights.

5. The combination as in claim 3 wherein the rollers are each mounted on an arm and each arm is pivotally mounted to move the rollers into and out of engagement with the end faces of the articles in the specified timed relationships.

10 6. A combination as in claim 5 wherein an air motor is provided for pivoting said arms to so move the rollers and switch means are provided for actuating operation of said motors dependent on the points of advance of the leading and trailing edges of the articles.

15 7. A combination as in claim 3 wherein each roller is mounted on a hollow spindle journaled on an arm, a slip ring assembly is secured to the lower end of each spindle and connections are provided for supplying current to energize heating elements for said rollers, and further wherein a bracket is provided for each arm, each bracket having a post for the pivotal mounting of the arm associated therewith.

20 8. A combination as in claim 7 wherein each of said posts is hollow and a shaft extends therethrough with a sprocket at its other end, each hollow spindle has a sprocket thereon, chains connect the shaft sprockets and spindle sprockets respectively, and means are provided for rotating said shafts to thereby provide the means for rotating said rollers.

25 9. A combination as in claim 8 wherein said brackets are slidably mounted on a fixed member disposed transverse to the path of advance of said articles and the means for rotating said shafts comprises a gear secured to the lower end of each shaft, a transverse rotating shaft, gears slidably mounted on said shaft and meshing respectively with the aforesaid gears, said brackets having portions 30 positioning said slideable gears in meshing relation with the first mentioned gears whereby the heat sealing rollers may be adjusted for different widths of articles.

35 10. A combination as in claim 9 wherein each roller comprises a central cylinder, a plurality of rings of different heights telescoped thereover and a separator of lesser diameter than said rings also telescoped over said cylinder and adapted to separate one or more of the lower rings having the specified height less than that of the article end faces from the remainder of the rings and means for releasably holding said rings and separator in assembled relation on said cylinder whereby the rings and separator may be readily positioned on said cylinder to obtain the proper height of surface for engaging a wide range of article heights.
